VALVE FOR POWER TRANSMISSIONS

L. Raymond Twymen, Bloomfield Township,
Oakland County, Mich.

Application September 13, 1946, Serial No. 696,650

4 Claims. (Cl. 251—27)

1

This invention relates to power transmissions, particularly to those of the type comprising two or more fluid pressure energy translating devices, one of which may function as a pump and another as a fluid motor.

The invention is more particularly concerned with an improved variable throttle valve for use in such a power transmission as well as in other places where a variable orifice may be required. In the patent to Herman No. 2,343,375, there is disclosed a flow regulating valve of the type having a variable throttle and the compensating valve connected thereto, and arranged to be responsive to the pressure drop across the throttle in a manner to maintain that pressure drop constant and thereby maintain the flow rate through the throttle constant independently of pressure applied to the regulating valve as a whole. In the construction there disclosed, use is made of a thin edged orifice for the purpose of minimizing the effects of different viscosities of fluid passing through the valve.

Various constructions have been utilized for providing an orifice with thin edges and it is a relatively simple problem where the size of the orifice may be fixed. However, where the orifice size must be varied, as by a manual adjustment, it has heretofore been necessary to provide some sort of shutter action by which a portion of the maximum orifice opening is closed off by one or more sliding or rotating shutter members. Because the two relatively movable walls of the orifice must be in different members and in different planes, such constructions only approximate the desirable results obtained with a true thin edged orifice.

It is an object of the present invention, therefore, to provide an improved construction for a thin edged orifice wherein the orifice may be formed in one integral barrier member and may be varied in size by distortion of that member whereby perfect thin edged orifice action may be more closely approximated.

Another object is to provide an improved flow regulating valve having an adjustable throttle and a pressure responsive compensating valve in which the throttle comprises a single integral wall member having an opening the size of which may be varied.

Further objects and advantages of the present invention will be apparent from the following description, reference being had to the accompanying drawing wherein a preferred form of the present invention is clearly shown.

In the drawing:

Figure 1 is a transverse sectional view of a flow

2

control valve embodying a preferred form of the present invention.

Figure 2 is a sectional view on line 2—2 of Figure 1.

5 Figure 3 is a fragmentary view corresponding to a portion of Figure 1, with the parts in a different position.

Figure 4 is a fragmentary sectional view on line 4—4 of Figure 1.

10 Figure 5 is a fragmentary sectional view on line 5—5 of Figure 2.

In the preferred embodiment of the invention illustrated, the adjustable throttle has been incorporated in a flow regulating valve of the type 15 commonly used for maintaining regulated flow rates in fluid power transmission systems. It will be understood, of course, that the throttle construction is equally applicable to other uses where an adjustable thin edge orifice is desired as for 20 example in regulating flow of fuel oil and such devices as are disclosed in the Lum Patent 2,072,761 as well as for many other purposes.

Referring now to Figure 1, there is shown a flow control valve comprising a body 10 having a 25 transverse bore 12 for the reception of a pressure responsive compensating valve generally designated 14. The latter comprises a sleeve 16 retained in place by a shoulder 18 and an end plug 20, the opposite end of the bore 12 being closed by a plug 22. The sleeve 16 has an internal bore 24 provided with a series of controllable inlet ports 26 and a series of outlet ports 28. The ports 26 communicate with a groove 30 which in turn communicates with an inlet passage 32. The ports 28 communicate with a groove 34, which in turn communicates with an intercepting vertical bore 36. Positioned in the bore 24 is a valve spool 38 having a land 40 adapted to open or close the ports 26. The valve spool 38 is provided with an integral piston head 41 40 slidable in the left hand end of bore 12. A longitudinal passage 42 connects ports 28 with opposite ends of the sleeve 16, thereby applying the pressure existing in ports 28 to the right hand end of valve spool 38 and to the right hand surface of piston 41. A spring 43 normally urges the spool and piston to the right with a light force.

50 Referring now to Figure 2, the lower end of bore 36 opens to the left into a larger transverse bore 44 and is provided with a rounded oval throat at 46 which is of oval cross-section as viewed in Figure 1. Slidably mounted in bore 44 55 is an orifice member 48. The latter has a cylindrical surface which is slidable in the bore 44 and provided with a sealing ring 50 as well as a

keyway 52 for co-operation with a pin 54, to prevent rotation of the member 48. At its right hand end, the member 48 is formed with a substantially hemispherical thin wall 56.

The wall 56 is preferably formed as a surface of revolution about the axis of the member 48 and thus is provided with a compound curvature, convex face presented to the oval throat 46. The wall 56 is provided with a slit 58, the walls of which are normally substantially in contact with one another or may be spaced from each other by a very small distance. The slot 58 extends vertically across the short diameter of the oval throat 46. Member 48 may be formed of any suitable hard springy material such as hardened steel, phosphor-bronze, beryllium copper, or any of a number of plastic materials and the wall 56 is sufficiently thin so that it may be readily distorted by the application of force substantially in the direction of the arrows shown in Figure 2.

At its left-hand end, the member 48 is closed by a plug 60 and is provided with a plurality of radial holes 62. The plug 60 is adapted to co-operate with a stationary seat 64 positioned in the right-hand end of bore 44 by a screw plug 66. The latter carries a threaded adjusting rod 68 having a dial 70 by which the member 48 may be adjustably shifted in the bore 44. The space to the left of seat 64 connects with an outlet passage 72 which in turn is connected with a vertical passage 74 communicating with the right-hand end of bore 12. Communication between passages 72 and 74 is by an intermediate passage 76 which extends to the back face of the body 10 and may form an outlet port for the valve as a whole.

In operation with the parts in the position as illustrated in Figures 1 and 2, the valve is closed and any fluid pressure admitted at the inlet passage 32 which may be directed through groove 30, holes 26, passages 28, groove 34, passage 36, and throat 46 is principally blocked at the flexible wall 56 because the slot 58 is closed. If the walls of the slit do not form a perfect seal, any leakage therethrough will be transmitted to the interior of member 48 and through the holes at 62 to the interior of bore 44 where it is blocked by the plug 60 being seated on seat 64. Thus the valve is closed tight and the build-up of pressure in the passages just described will be transmitted through passages 42 to the right-hand face of spool 38 and piston 41 and shift the spool 38 to the left closing the passages 26. Pressure in the outlet port 76 being low and acting over the left-hand face of piston 41 permits such leftward movement of the spool 38.

When it is desired to open the valve and permit a regulated rate of flow therethrough, the dial 70 is turned to screw the stem 68 inwardly carrying the plug 60 off of the seat 64 and bringing the convex wall 56 into engagement with the oval seat 46 at approximately the point shown by the arrows in Figure 2. As the member 48 is moved into engagement with the seat further, the flexible wall 56 is distorted in a direction tending to bring the ends of the slit 58 closer to each other which results, due to the curved shape of wall 56, in an opening of the central portion of the slit as shown in Figure 3. The degree of opening depends, of course, upon the amount of inward movement given to the screw 68 so that the slit 58 may be varied in area over a substantial range. With the slit 58 open, the action is similar to that described in the Herman patent re-

ferred to in that the valve 14 takes up a position depending upon the difference in pressure between that at the inlet 32 and the back pressure at outlet 76, so that a throttling effect occurs between lands 48 and holes 26 sufficient at all times to maintain a constant pressure drop across the orifice represented by the slot 58.

It is well understood that the maintenance of a constant pressure drop across an orifice of a given size results in a constant rate of flow therethrough with fluid of any given viscosity. Furthermore, by reason of the fact that the wall 56 is thin and the edges of the slit 58 are consequently comparatively sharp or thin the flow rate will also remain substantially constant over a substantial range of viscosities.

It will thus be seen that the present invention provides a throttling device and flow regulating valve in which a constant flow rate may be maintained with only negligible or very small variations regardless of large variations in the pressure applied to the valve as a whole and also large variations in oil viscosity.

While the form of embodiment of the invention as herein disclosed constitutes a preferred form, it is to be understood that other forms might be adopted, all coming within the scope of the claims which follow.

What is claimed is as follows:

1. An adjustable throttle for controlling fluid flow comprising a thin wall member forming a barrier in a fluid channel and having a configuration in a curved surface of revolution, and being formed of a springy hard material, said wall having a slit extending therethrough, a co-operating member of non-circular form, and means for varying the relative engagement of the wall member and the non-circular member for variably deforming the wall member whereby the slit may be opened to a variable extent.

2. An adjustable throttle for controlling fluid flow in a channel comprising a thin, metallic, convex wall member forming a barrier in the channel and having a slit therethrough, and shiftable means within the fluid channel for variably deforming the member endwise of the slit to create an adjustable orifice having a thin edge.

3. An adjustable throttle for controlling fluid flow in a channel comprising a thin, metallic, convex wall member forming a barrier in the channel and having a slit therethrough, a non-circular seat member engageable with the wall member and means for shifting one of said members relative to the other to variably compress the wall member and variably open the slit.

4. An adjustable throttle for controlling fluid flow in a channel comprising a thin, metallic, convex wall member forming a barrier in the channel and having a slit therethrough, a stationary oval seat member, and means for variably forcing the wall member into engagement with the seat to variably compress the wall member endwise of the slit whereby the slit may be variably opened to form an adjustable thin edged orifice.
